UNITED STATES PATENT OFFICE.

EMMA F. ADAMS, OF KANSAS CITY, MISSOURI.

DESIGN FOR A GAME-BOARD.

SPECIFICATION forming part of Design No. 32,518, dated April 10, 1900.

Application filed February 5, 1900. Serial No. 4,144. Term of patent 31 years.

To all whom it may concern:

Be it known that I, EMMA F. ADAMS, a citizen of the United States, residing at Kansas City, in the county of Jackson and State of Missouri, have invented and produced a new and original Design for a Game-Board, of which the following is a specification, reference being had to the accompanying drawings, forming part thereof.

Figure 1 is a perspective view of a game-board, showing my new design. Fig. 2 is a vertical sectional view taken on the line II II of Fig. 1.

As shown in the drawings, the leading or material features of my design include a box-like structure having a flat base A, vertical sides B, a sloping end C, disposed at an obtuse angle to the base A, and a top consisting of two portions, one of which, D, is parallel to the base A and has a series of circular vertical perforations E extending through it.

The other portion of the top F is inclined at an angle, sloping from a point some distance from said perforations to the opposite end of the base, which it meets at an acute angle. 25 The portion D of the top does not extend to the sloping end wall C, a rectangular opening G being left between said portion D and said wall. Said end wall C extends upwardly considerably above the top D, and its upper edge 30 has an upwardly-curving oval outline.

Having described my invention, I claim as new and desire to secure by Letters Patent—

The design for a game-board, as herein shown and described. 35

In testimony whereof I affix my signature in the presence of two witnesses.

EMMA F. ADAMS.
